UNITED STATES PATENT OFFICE.

JAMES LYONS, OF BROOKLYN, NEW YORK, ASSIGNOR, BY MESNE ASSIGNMENTS, TO EISENBREY MANUFACTURING COMPANY, OF BALTIMORE, MARYLAND, A CORPORATION OF DELAWARE.

DESIGN FOR A BED-CABINET.

41,996.

Specification for Design.

Patented Dec. 19, 1911.

Application filed August 9, 1909. Serial No. 512,084. Term of patent 14 years.

To all whom it may concern:

Be it known that I, JAMES LYONS, a citizen of the United States, residing at Brooklyn, in the county of Kings and State of New York, have invented a new, original, and ornamental Design for Bed-Cabinets, of which the following is a specification, reference being had to the accompanying drawing, forming part thereof.

The figure is a perspective view of a bed cabinet showing my new design.

I claim:

The ornamental design for a bed cabinet, as shown.

JAMES LYONS.
